(57) **CLAIM**

The ornamental design for a blank for forming a guard, as shown and described.

DESCRIPTION

FIG. 1 is a front elevational view of an ornamental design for a blank for forming a guard;

FIG. 2 is a rear elevational view thereof;

FIG. 3 is a partial enlarged view thereof according to the broken rectangle "3" shown in FIG. 1;

FIG. 4 is a left side elevational view of FIG. 1;

FIG. 5 is a right side elevational view thereof;

FIG. 6 is a top plan view thereof; and,

FIG. 7 is a bottom plan view thereof.

The break lines of FIGS. 1, 2, 4, and 5 are indicative of indeterminate length and form no part of the claimed design. The appearance of any portion of the article between the break lines forms no part of the claimed design. The dash-dot-dot-dash broken lines are included for the purpose of illustrating fold lines and form no part of the claimed design.
